188,979

DRESS OR SIMILAR ARTICLE

Ceil Chapman, 530 7th Ave., New York, N.Y.

Filed June 13, 1960, Ser. No. 60,944

Term of patent 3½ years

(Cl. D3—26)

Fig. 1 is a front view of a dress showing my new design.

Fig. 2 is a rear view thereof.

Fig. 3 is a front view on a reduced scale of the dress shown in Fig. 1 as it appears with the belt removed.

Fig. 4 is a rear view of Fig. 3.

Fig. 5 is another front view of the dress shown in Fig. 1 as it appears with the panel portion drawn to one side to illustrate the dress closure.

I claim:

The ornamental design for a dress or similar article, substantially as shown.
